UNITED STATES PATENT OFFICE.

GEORGE S. WHITAKER, OF GLOVERSVILLE, NEW YORK.

VACUUM-CUP-FASTENING MEANS FOR DENTAL SUCTION-PLATES.

1,343,949.

Specification of Letters Patent. Patented June 22, 1920.

Application filed August 19, 1919. Serial No. 318,519.

To all whom it may concern:

Be it known that I, GEORGE S. WHITAKER, a citizen of the United States, residing at Gloversville, in the county of Fulton and 5 State of New York, have invented a new and useful Vacuum-Cup-Fastening Means for Dental Suction-Plates, of which the following is a specification.

This invention has reference to vacuum 10 cup fastening means for dental suction plates, and its object is to provide for the fastening of a suction cup, formed separately from a denture, in the suction cavity of the denture in such manner that no metal 15 whatever can come into contact with any part of the tissues of the mouth of the user and the cup is held in place against liability of accidental loosening or becoming detached, although readily applied or detached 20 when desired.

The invention is along the same general lines as that disclosed in my Letters Patent #1,253,654, for dental retainer and process of making same, granted January 15, 1918, 25 and in some respects is similar to the structure shown and described in an application Serial No. 318,520 for dental suction plate filed by me on even date herewith.

In accordance with the invention the denture is provided with a suction cavity having at its bottom a screw socket, and a suction or vacuum cup of flexible material, such as soft rubber, is provided and furnished with a screw plug so arranged as to 35 screw tightly into the socket but is at the same time capable of being removed therefrom for cleansing or repairs. The screw plug and screw socket form two coacting members of a fastening device and each 40 member is vulcanized in the vacuum cup and body of the denture respectively. The vulcanizing of the parts in place constitutes a particularly reliable mode of uniting in a permanent manner the fastening means to 45 the parts to be secured together with the arrangement such that there is no possibility of metal parts, of which the fastening means are usually made, coming in contact with the tissues of the mouth.

50 The invention will be best understood from a consideration of the following detailed description taken in connection with the accompanying drawing forming part of this specification, with the understanding, 55 however, that the invention is not confined to any strict conformity with the showing

of the drawing, but may be changed and modified so long as such changes and modifications mark no material departure from the salient features of the invention as expressed in the appended claims. 60

In the drawing:—

Figure 1 is a longitudinal vertical section through a denture provided with the invention. 65

Fig. 2 is a diametric section through the suction or vacuum cup alone.

Fig. 3 is a bottom plan view of the suction cup of Fig. 2.

Fig. 4 is a section through that portion 70 of the denture including the suction cavity and showing a screw socket anchored in the denture.

Fig. 5 is a plan view of the structure shown in Fig. 4. 75

Fig. 6 is a section through a mold plate with the screw socket applied thereto for molding the suction cavity of the denture and anchoring the screw socket in the denture. 80

The showing of the drawing is on an exaggerated scale in order that small parts may be clearly shown.

In the drawing, there is shown a denture 1 in the upper or roof portion of which 85 there is produced a suction recess or cavity 2 with undercut walls 3 similar to the arrangement of the aforesaid Letters Patent. There is also provided a suction or vacuum cup 4 with beveled peripheral walls 5 and a 90 thickened basic portion 6, these parts being in the main similar to like parts shown in the aforesaid Letters Patent.

The vacuum cup 4 which is of more or less conical form, is so constructed as to seat 95 in the central portion of the recess or cavity 2 where there is formed a central depression 7 with a continuation 8 of smaller diameter and centralized with respect to the main part of the depression 7. The basic portion 100 6 is of a size to fit snugly into the depression 7 and in the basic portion 6 there is lodged a plate 9 having a screw stem 10 projecting from one face thereof, the plate 9 being of considerably greater diameter 105 than the stem 10. In order to secure the threaded stem 10 with its plate 9 firmly in the basic portion 6 the plate 9 is embedded in the basic portion and vulcanized therein so that the material of the base 6 completely 110 incloses the plate and a portion of the stem 10, leaving the free end of the stem project-

ing from that face of the base 6 remote from the interior of the cup 4. The plate 9 is provided at suitable intervals outside of the stem 10 with perforations 11 traversed by the material of the base 6 whereby to anchor the plate and stem against displacement in the base 6, thus making the union permanent.

The suction cavity 2 is formed, in the 10 production of the denture, by means of a mold plate 12 having a beveled periphery 13 corresponding to the undercut portion 3 of the suction cavity. At the mid-portion of the mold 12 is a projection 14 on one 15 face thereof and centrally of the projection 14 is a stem 15 on the side of the projection 14 remote from the plate 12.

There is also provided a socket member 16 of a size to fit into the cavity extension 8 20 and this socket member has at its open end a marginal flange 17 of greater diameter than the depression 7 and outside of the latter provided with perforations 18. When 25 producing the denture 1 the plate 12 is made fast to the dental mold and the socket 16 is applied to the stem or projection 15, leaving the flange 17 in part beyond the outer margins of the projection 14 so as to be in spaced relation to the adjacent face 30 of the plate 12. When the material of which the denture 1 is made is placed against the dental mold to the required depth, some of the material is forced through the perforations 18 and into the 35 space between the flange 17 and the adjacent face of the plate 12. When the denture is vulcanized the socket 16 thereby becomes embedded and anchored in the denture, the socket, which is usually of metal, preventing 40 any of the material of the denture from entering the space occupied by the socket. After the denture has been properly vulcanized the plate 12, which may be suitably treated either as described in the afore- 45 said Letters Patent or in any other suitable manner to prevent the vulcanizable material from sticking to it, is withdrawn, thereby leaving the cavities 2 and 7 and also leaving the socket 16 permanently embedded in the denture.

In order to apply the suction or vacuum cup 4 it is only necessary to screw the stem 10 into the socket 16 which is correspondingly screw-threaded and the parts are so 55 proportioned that when the cup 4 is screwed tight the base 6 is seated against the upper surface of the flange 17 and the cup 4 is

centralized with relation to the cavity 2. When the denture is placed in the mouth of the user the cup 4 is flattened out so that 60 the margins 5 enter the cavity 2 but the cup is so proportioned that the beveled margins 5 are a little short of fitting the undercut portions 3 of the cavity 2. This soon becomes remedied, however, by the swelling 65 and expansion of the cup 4 by the heat and moisture of the mouth of the user so that the denture is very firmly held in the mouth against accidental displacement, although it will yield to purposely applied forces 70 when it is desired to remove the denture from the mouth. All metallic parts represented by the fastening device consisting of the screw stem 10 and screw socket 16, are thoroughly protected by the material of 75 the base 6 from contact with the tissues of the mouth of the user. At the same time the cup 4 may be readily unscrewed from the socket 16 for cleansing or renewal purposes. 80

What is claimed is:—

1. A dental plate provided with a suction cavity and a separate vacuum cup to coact therewith, and a two-part fastening device for securing the cup to the dental plate 85 within the suction cavity, comprising a screw stem with a headed end wholly embedded and anchored in the basic portion of the vacuum cup and protected thereby from contact with the tissues of the mouth 90 of the user, and a screw socket embedded and anchored in the dental plate at the bottom of the suction cavity.

2. A dental plate provided with a suction cavity and a separate vacuum cup to 95 coact therewith, said cup having a thickened basic portion, and a two-part fastening means for securing the cup to the dental plate, comprising a screw-threaded stem 100 with an expanded end embedded and vulcanized in the basic portion of the cup, and a screw socket for receiving the stem and provided with an outstanding flange at the open end, said socket and flange being embedded in the body of the dental plate in 105 substantially centralized relation to the suction cavity and vulcanized in place.

In testimony that I claim the foregoing as my own, I have hereto affixed my signature.

GEORGE S. WHITAKER.

Witness:

EDWARD FONDA.
